UNITED STATES PATENT OFFICE

GUY T. GIBSON, OF NEW ROCHELLE, NEW YORK, ASSIGNOR TO GUY T. GIBSON, INCORPORATED, OF NEW YORK, N. Y., A CORPORATION OF NEW YORK

DESIGN FOR A CARTON

Application filed January 8, 1932. Serial No. 42,414. Term of patent 14 years.

To all whom it may concern:

Be it known that I, GUY T. GIBSON, a citizen of the United States, and resident of New Rochelle, in the county of Westchester and State of New York, have invented a new, original, and ornamental Design for a Carton, of which the following is a specification, reference being had to the accompanying drawings, forming a part thereof:

Fig. 1 represents a plan view of a carton, showing my new design;

Fig. 2 represents a front elevation of the same; Fig. 3 represents a side elevation of the same, and Fig. 4 represents a rear elevation of the same.

I claim:

The ornamental design for a carton substantially as shown.

GUY T. GIBSON.
